Primary Examiner — Ruth McInroy(74) *Attorney, Agent, or Firm* — Hodgson Russ LLP(57) **CLAIM**

The ornamental design for a swimming pool vacuum, as shown and described.

DESCRIPTION

FIG. 1 is a front-right-top perspective view of a first embodiment of a swimming pool vacuum showing my new design; FIG. 2 is a rear-right-bottom perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; and, FIG. 8 is a bottom plan view thereof.
The broken lines illustrate unclaimed portions of the swimming pool vacuum that form no part of the claimed design.
